[57] CLAIM

The ornamental design for a control panel for a room air conditioner, as shown and described.

DESCRIPTION

FIG. 1 is a front elevational view of a control panel for a room air conditioner showing our new design;

FIG. 2 is a left side elevational view thereof;

FIG. 3 is a top plan view thereof;

FIG. 4 is a bottom plan view thereof;

FIG. 5 is a right side elevational view thereof; and,

FIG. 6 is a perspective view illustrating the bottom plan view, right side elevational view and the front elevational view.

The broken line showing environmental structure in FIGS. 1-6 is for illustrative purposes only and forms no part of the claimed design.

The rear of the design is flat and unornamented.

FIG.5FIG.3FIG.1FIG.4FIG.2

FIG. 6
